UNITED STATES PATENT OFFICE.

THOMAS MORTON, OF NEW YORK, N. Y.

SASH-BALANCE.

SPECIFICATION forming part of Letters Patent No. 315,533, dated April 14, 1885.

Application filed September 13, 1884. (No model.)

To all whom it may concern:

Be it known that I, THOMAS MORTON, a citizen of the United States, residing at New York, in the county of New York and State of New York, have invented a new and useful Improvement 5 in Sash-Balances, of which the following is a specification, reference being had to the accompanying drawings.

This invention relates to sash-balances, and 10 to that class of the same in which weights are used to connect with the sashes; and it has for its object to provide means for connecting the weight to the chain with ease and readiness, the attachment being strengthened, and a saving 15 being made in the links of the chain. With these and other objects in view the said invention consists in certain details of construction and combination of parts, as herein-after set forth, and particularly pointed out in 20 the claims.

In the accompanying drawings, Figure 1 is a view, partly in elevation and partly in section, showing my improvements applied to a sash. Fig. 2 is a view illustrating the old 25 method of attaching the weight to the chain. Fig. 3 is a detail view of my improvements.

Like letters are used to indicate corresponding parts in the several figures.

Referring to the drawings, A is the window-frame, and B the sash. The former is made 30 with the ordinary weight-box and pulleys, and the latter with the usual chain-groove, at the lower termination of which is a circular recess for the reception of the bracket or fastener for the end of the chain. In Fig. 1 I have 35 shown the old method of connecting the chain to the sash, and since I do not claim anything in the arrangement shown, I deem it unnecessary to particularly recite the construction.

To the lower link of the chain is attached a 40 U-shaped clip, C, having its arms *a a* provided with eyes *b b*, said arms being turned laterally in different directions.

D designates the loop, made with two springing- 45 arms, *d d*, the lower closed end of the loop receiving the weight, while the upper ends of the arms are turned down to form hooks *e e*, which are passed through the holes or eyes *b* in the clip C.

The operation of my improvement and the 50 attachment of the same will be readily under-

stood from the foregoing description, taken in connection with the annexed drawings.

The chain is fastened at one end to the bracket, fitted in the sash, passes over the pulley, the 55 clip C being connected with the lower link of the chain. The arms of the clip are so disposed and turned that the eyes *b* are away from each other. In attaching the loop to the clip the arms *d* are pressed inward until the 60 distance between the hooks *e* corresponds with the distance between the eyes or holes *b*, when said hooks can be slipped through the eyes, and thus complete the attachment. Of course the loop is slipped through the hole in the 65 weight before attachment is made with the clip.

In the ordinary method of attaching the weight to the chain (shown in Fig. 2) a loop or hook is employed having arms of unequal 70 length, provided with hooks, the hook of the short arm engaging directly the lower link of the chain, while the hook of the longer arm engages with a third link on the same chain.

By this arrangement three links are unnecessarily wasted in the attachment of the weight, and as the chain is very expensive, and there are four weights to each window, it will be seen that this wasting of three links soon amounts to a considerable item. My invention obviates 75 this objection by the employment of the clip and improved form of loop hereinbefore described, and, besides, forms a simple and easily applied attachment, which will be stronger than the one in general use.

It will be observed that the attachment of the clip to the link is effected by passing the clip through the slot in the wall of the link, the arms of the clip depending downward and sprung laterally outward in opposite directions to receive the hooked upper ends of the loop.

My attachment, as before stated, affords a considerable saving in the chain, and is more readily applied than the present form of sash-balance. It is simple, inexpensive, and efficient, and will prove of great utility for the 90 purposes intended.

Having described my invention, I claim—

1. The herein-described clip for attaching the 100 chain to the weight-securing hook or loop, formed of a single piece of metal in U-shaped

form, the arms of the clip being sprung laterally in opposite directions and perforated, so that said arms both face on a line with each other, as and for the purpose set forth.

- 5 2. The combination, with the sash-chain, of a clip connected to the lower end of the same, and comprising two arms which are bent laterally in opposite directions, eyes formed in said arms, and the weight-securing hook or loop having its arms of equal length, the up-

per hooked ends of the arms engaging with the eyes of the clip, as set forth.

In testimony that I claim the foregoing as my own I have hereto affixed my signature in presence of two witnesses.

THOMAS MORTON.

Witnesses:

THOMAS S. MORTON,
JOS. SHERIDAN.
